BLADE MOUNTING MEANS FOR MULTIPLE BLADE BREAD SLICING MACHINES

Filed June 9, 1945

UNITED STATES PATENT OFFICE

2,437,123

BLADE MOUNTING MEANS FOR MULTIPLE
BLADE BREAD SLICING MACHINESCharles H. Petskeyes, Davenport, Iowa, assignor
to Gellman Manufacturing Company, Rock
Island, Ill., a corporation of Illinois

Application June 9, 1945, Serial No. 598,458

1. Claim. (Cl. 146—153)

1

This invention relates to certain novel improvements in blade mounting means for a multiple blade bread slicing machine. More specifically the invention has reference and relates to means for mounting the slicing knives of such machine upon reciprocating frames in a manner such that the knife mounting means may be expeditiously removed for purposes of varying the space between the knives. In this aspect of the invention the primary object is to provide a structure which will be highly efficient in use, economical in manufacture, and simple in construction.

A still further and equally important object of the invention is the provision for bodily and severally mounting slicing knives in a predetermined spaced relation with respect to each other upon a reciprocable frame of a bread slicing machine, thereby affording either bodily or several removal of the knives for repair or replacement purposes or for purposes of varying the space between the knives.

The present invention is especially adaptable to slicing frames of a bread slicing machine such as that shown in my copending application, Serial No. 598,457, filed June 9, 1945, and constitutes an improvement over the bread slicing machine shown in United States Patent No. 2,092,276.

Other objects will appear hereinafter:

The invention consists in the novel combination and arrangement of parts to be hereinafter described and claimed.

The invention will be best understood by reference to the accompanying drawings showing the preferred form of construction, and in which:

Fig. 1 is a side elevational view of a frame and its mounting saddle, showing the invention associated therewith;

Fig. 2 is a vertical sectional detail view through oppositely disposed frames and their saddles;

Fig. 3 is a fragmentary perspective view of a bracket bar embodied in the invention.

The drawings illustrate the preferred form of construction of my invention by which the several objects of the invention are accomplished, and in this connection 10 and 11 indicate frame members. These frame members are slidably associated with saddles 12 and 13 in a manner fully shown and described in my copending application. These saddles are reciprocated vertically in opposite directions with respect to each other through the medium of reciprocating rods 14 and 15, the reciprocation being affected in a manner substantially similar to that described in the aforesaid copending application and the 55

2

frames guided in such movement by rods 15' carried by mounting brackets 14' secured to the wall 13' of the housing 12' of the machine.

Each frame comprises a plurality of elongated knives 16 spaced substantially with respect to each other, with the knives of one frame disposed between the knives of the other frame and reciprocating in opposite directions with respect to each other. The space between the knives determines the thickness in which the bread is to be sliced, and in the present construction it is found desirable that the mountings of these knives be such as to permit their mountings to be removed to permit similar mountings to be replaced therefor, with the exception that the knife supports of the mountings are either spaced closer or farther away from each other, thereby to permit association with the frames, of knives of greater or lesser space therebetween.

To accomplish this and other objects of the invention, I mount upon the top rail 17 of each frame a mounting plate 18. This mounting plate 18 along one longitudinal edge 19 is provided with an elongated groove 20 which receives the marginal edge portion 21 of the top flange 22 of the top rail 17, the said marginal edge portion being provided with a shoulder 23 which serves to limit the projection of the marginal edge into the groove 20.

Extending upwardly from this mounting plate 18 is a stud shaft 24 threaded at its outer extremity as at 25 to receive a pair of nut elements 26.

The mounting plate 18 at its edge portion opposite the marginal edge portion 19, is angled upwardly as at 27 and at predetermined points there are provided spaced slots 28 through which project the end portions 29 of latch bars 30. The inner end portions of these latch bars 30 are each bifurcated as at 31 to receive the stud shafts 24. Disposed between suitable washers 32 arranged between the nut elements 26 and the latch bars 30, are spring members 33 which act upon the latch bars to pivot them in an anticlockwise direction.

The end portions of each of the latch bars each are provided with a notch 35 adapted to receive the hanger pin 36 carried at the upper end portion 39 of each of the knives 16.

Secured to the side wall 40 of each frame 10 and 11, by means of a nut receiving bolt 41, is a bracket 42, the horizontal portion of which is notched as at 43 to receive the anchor pin 45 carried at the lower end of each of the knives 16.

By adjusting the nut elements 26, the springs

33 may be compressed and the tension thereof increased to increase the leverage of the latch bars 30 upon the pins 36 and thus maintain the knives 16 in substantially taut condition, preventing their side-swaying or warping during the slicing operation. Should it be found that a lesser or greater space is desired between the knives 16, all the knives 16 may be removed from their respective mountings, after which the mounting plate 18 and the bracket 42 are removed and a similar mounting plate and bracket substituted therefor, but with the slots in the angled end portions 27 spaced nearer or farther apart so as to result in having knives mounted upon the frame spaced at different distances from those shown in the drawing.

From the foregoing description, it is obvious that in the event of replacement of a knife, the knives may be individually removed, this being accomplished by merely releasing the tension upon the spring 33, which allows the latch bar 30 to pivot freely for disconnection of the pin of the knife from the notch 35 and of the pin of such knife from the bracket 42.

Upon the foregoing premises the knives may be either bodily or severally removed from mounted position upon the frames.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

Means for connecting corresponding upper end

portions of a plurality of spaced knives to the upper rail of the frame of a slicing machine comprising a mounting bar fixed to the upper rail and having an inclined upwardly extending portion provided with a plurality of open slots spaced equally apart with respect to each other, a plurality of levers removably fulcrumed on said bar in said slots, and having corresponding end portions bifurcated and opposite end portions each provided with a notch adapted to removably receive the hanger pin carried by a slicing knife, spaced mounting studs carried by the mounting plate and projecting through the bifurcated portions of the levers to stabilize said levers, and spring means carried by the mounting studs and engageable with adjacent portions of said levers to pivot said levers upon said bar in a direction opposite to the pivotal movement of said levers by action of the slicing knives.

CHARLES H. PETSKEYES.
